Patented Dec. 14, 1965

203,187

MICROPHONE

Robert Louis Deschamps, West Chicago, Ill., assignor to
Shure Brothers Incorporated, a corporation of Illinois

Filed Aug. 10, 1964, Ser. No. 81,230

Term of patent 14 years

(Cl. D26—14)

FIGURE 1 is a front elevational view of a microphone, illustrating my new design;
FIGURE 2 is a left side elevational view;
FIGURE 3 is a rear elevational view;
FIGURE 4 is a right side elevational view;
FIGURE 5 is a top plan view;
FIGURE 6 is a bottom view; and
FIGURE 7 is a fragmentary cross-sectional view thereof taken through the microphone openings at the front of the microphone.

I claim:

The ornamental design for a microphone, substantially as shown.
